VEHICLE FOR THE TRANSPORT OF A ROTATING MIXER OR THE LIKE

CROSS-REFERENCES TO RELATED APPLICATIONS

This is an improvement of the invention defined in U.S. Pat. No. 3,521,767 issued July 28, 1970 and entitled VEHICLE FOR THE TRANSPORT OF A ROTATING MIXER, OR THE LIKE, PROVIDED WITH CONTINUOUS CONVEYOR, Lionello Rossi, inventor.

DESCRIPTION OF THE PREFERRED EMBODIMENTS

In U.S. Pat. No. 3,521,767, aforesaid, provision has been made for a conveyor for the transport of loose materials or mixtures, said conveyor adapted to mounting on vehicles carrying a rotating mixer and being divided into a plurality of longitudinal sections, articulated as to each other and at least in part extendible and of a foldable type, means being provided for moving said conveyor sections to occupy very little space and to cause them to be moved outward in a fully operative extended working condition. The present invention is adapted to improve the system defined by said U.S. Pat. No. 3,521,767 wherein a combination of devices associated with the conveyor ensures a greater compactness of unit, while at the same time allowing more readiness, reliability and efficiency of operation.

Referring to the drawings:

FIG. 1 illustrates the top of a partial first section of the conveyor and of the other two sections folded, the sections being adapted to travel along a slide channel arranged in the frame of the vehicle;

FIG. 2 is a side view of a portion of the conveyor in its folded position as it occupies the minimum space, reference stand still position of FIG. 1;

FIG. 3 shows the front view of the conveyor in the folded position of FIG. 1, taken along the lines F-F of FIG. 2;

FIG. 4 shows a side view of the carriage for dragging the first section of the conveyor and of the locking system associated therewith;

FIG. 5 is a schematic top plan view of the FIG. 4 carriage and its housing;

FIG. 6 is a longitudinal fragmental side view of the FIG. 5 device;

FIGS. 7a and 7b illustrate the FIG. 6 operation of locking lever taken along the lines C-C of FIG. 6;

FIG. 8 is a side view of the conveyor support framework with parts removed.

For clarity reference numerals in all of the drawings indicate new or improved elements are numbered at 200 and above, while the lower numerical designations indicate parts which have been disclosed in U.S. Pat. No. 3,521,767, aforesaid.

According to the present invention, a single casing 204 is located above the longitudinal slide channel 18, the channel being provided to house extendible section 7 of the conveyor and the casing 204 being provided to house the two grooved drums around which will be wound the traction cables 29 and 34, the traveling of said section along said channel 18 occurring simultaneously as cable 29 is unrolling and being proportionated with the length of the unrolled cable. For better utilization of the conveyor, provision has been made to use a pulley 31 having a movable and swinging arrangement, said pulley being mounted at the top of framework 42, an integral part of the vehicle whereby its supporting member is connected to framework 42 by means of a hinge 31a, the pivot axis of which is horizontal and parallel to the longitudinal center vertical plane of the vehicle; thereby allowing the conveyor to be easily turned about a vertical axis through an angle of 90° in relation to said vertical longitudinal center plane of vehicle 1.

The support 201 supports motor 202, the control devices 203 and the casing 204 housing the grooved drums 33 and 39, as well as the driving pulley 36a of cable 34. By means of a hook the cable drags the section 7 slidingly along said channel 18.

Cable 34 instead of traveling into the gap formed between the mud guard panel of the vehicle where the mixer is mounted and the lower part of channel 18, travels freely parallel to said channel 18 and above it, whereby cable 34 does not bear against the mud guard. Of course, provision must be made to mount the pulley 35a (reference FIG. 6) on post 205 at a height sufficient to allow it to operate in a substantially horizontal plane. Hydraulic jack 206 is mounted on the carriage 21, said jack causing rotary movement of the conveyor about a vertical axis, passing through the pivot 22 of the hinge-connecting section 7 and the carriage 21 in combination with a second hinge 299, the axis of which is horizontal and set at a right angle with respect to the path direction of carriage 21. The jack 206 is eccentrically positioned relative to pivot 22 and acts on plate 72, said plate being integral with one of the parts of the hinge 299, so as to force section 7 together with other sections 8 and 9 of the conveyor, while aligned to rotate about the axis 22 through an angle of 90° towards the outer side of the housing 18, said position of plate 72 being shown in phantom lines in FIG. 5.

The prior art system represented by U.S. Pat. No. 3,521,767 required a substantial amount of skill and diligence on the operator in dragging the carriage 21 to specified arrest position before folding and unfolding the respective sections 7, 8 and 9, and performing rotary movement of the conveyor about the vertical axis. To overcome the inconvenience, an improved locking system is provided herein, preventing carriage 21 from an undesired return to housing 18, and to prevent any swinging movement towards the left or the right of the conveyor as the folding and unfolding phases take place. Reference FIG. 4, there is provided a vertical plate 210 which is connected to a control arm 210a projecting sideways; said plate 210 being pivotally connected to a lever 213, pivoted at 220 to the frame of the carriage 21. The plate 210 as well as the control arm 210a have two operative positions, namely a lower position, where plate 211, which may rotate about its supporting pin 212, acts on said arm 210a and holds it in said lower position together with the plate 210. There is also an upper position, which the control arm 210a can attain only as the plate 211 has been manually swung away from its stand still position, permitting the arm 210a and the plate 210 to be moved manually upwards and locked in their respective upper positions. As the plate 210 and the arm 210a may be in their lower positions, the lever 213 connected thereto is so positioned that a pin 214 extending upwardly from its free end is engaged within a hole 293 of the carriage frame, which is in register with a hole 294 arranged in the plate 72, only as section 7 may be exactly aligned with the carriage 21. Therefore, the control arm 210a and the plate 210 can attain said lower position only when the carriage 21 and the section 7 are aligned, namely as the conveyor is arranged to be moved so as to cause the section 7 to come into or out of the housing 18.

On the contrary, at the upper position, as the pin 214 is disengaged from the holes 293, 294 and the plate 210 is in its upright position, its upper edge 210' projects upwards and forms a stopping means abutting against the facing edge of the plate 211 or other part of the frame 2. The carriage 21 then may not be moved with respect to channel 18.

As soon as the carriage has been urged wholly out of the channel 18 and the lever 210 has been manually moved upwards, said lever causes the plate edge 210' to project upwards into contact with the outer surface 201 or other abutting means duly positioned so as to prevent the slide carriage 21 from returning into the housing 18. At the same time, pressure transmitted manually to the arm 210a causes the pin 214 to be lowered by means of the member 213 to which the plate 210 is connected. Said pin 214 will allow the plate 72, as well as the whole conveyor, to become free, the conveyor now being entirely positioned out of the casing 18 to now perform any rotary movement through angles of even 90° toward left or right as desired. When it is desired to fold the conveyor to its standstill position, the section is no more allowed to enter again into said channel 18 before the whole conveyor is set an angle of 180° in relation to the slide cage securely con-

nected to the vehicle. Only in this position can the pin 214 enter the hole duly disposed in the side plate which is connected to the rear end of the section 7, thus enabling the plate 210 to be lowered to its standstill position where it is locked by plate 211. This locking system will operate only as carriage 21 has been wholly extended from the channel whereby it may be locked at the end of its travel during the exit phase by means of an enlarged portion of the cable 34, said enlarged portion 296 being constituted of a pin inserted at a predetermined position along said cable.

Since concentric holes are provided in the body of the plate 210 as well as into the wall 215 of supporting member 216, said member being of C-shaped horizontal cross section, the cable is adapted to slide freely within to its arresting point. Holes 297 and 298 respectively are aligned only when control arm 210a and the plate 210 are in their upper operative position. Accordingly, the enlarged portion 296 of the cable 34 can freely pass throughout said holes. In such a manner the slide carriage 21 of the section 7 can no more move forward under the effect of forward driving.

I claim:

1. A conveyor for mixtures or loose materials of fluid consistency, adapted to motor vehicles for the transport of rotating mixers, characterized by operable movement of extendible-retractable conveyor sections the same being mounted on the frame of the vehicle for movement to and from a housing channel comprising:
  - A. a single casing disposed above a slide channel whereupon are mounted;
  - B. at least two grooved drums to wind and unwind a cable which is adapted to support and shift the conveyor;
  - C. a third drum to wind the cable in drawing said sections

out of the housing on the vehicle, all said drums being driven by;

- D. a single motor;
- E. a framework for carrying and raising the cable which draws said sections of the conveyor, said framework being so arranged as to compel said cable to move along its substantially horizontal plane parallel to and spaced apart from the slide channel, and positioned above it; and
- F. means for locking the slide carriage in at least one of the two end positions of travel thereof.

2. A conveyor according to claim 1, wherein the locking means for the slide carriage comprise a lever provided for manual operation and adapted to cause said locking means to move upward for engagement with abutting means, and a lever system controlled by said manually operated lever engaging a pin-plate fixed to the rear end of the slidable section of the conveyor so that the entire conveyor may be turned through an angle of 90° said traction cable having an enlarged portion adapted to abut against a restricted area formed in combination by two concentric holes, one of said holes being arranged in the body of the locking lever and the other into a wall supporting said locking lever.

3. The conveyor of claim 1, further comprising a movable pulley adapted to provide swinging movements of said conveyor, said pulley passing a cable for carrying and raising the conveyor to turn through angles including 90°.

4. The conveyor of claim 5, including hydraulic jack means interconnected with the outer sections of said conveyor whereby its eccentric positioning permits while said outer sections may be aligned the rotation thereof about an angle of 90°.
